US00D929965S

(12) **United States Design Patent** (10) Patent No.: **US D929,965 S**
Chandwani et al. (45) Date of Patent: **** Sep. 7, 2021**

(54) **WIRELESS CONTROLLER FOR SIMULTANEOUS MULTIPLE DEVICE OPERATION**

(71) Applicant: **KEUS AUTOMATION PRIVATE LIMITED**, Hyderabad (IN)

(72) Inventors: **Brijesh Chandwani**, Hyderabad (IN); **Subram Kapoor**, Hyderabad (IN); **Ashwik Reddy Battu**, Secunderabad (IN)

(73) Assignee: **KEUS AUTOMATION PRIVATE LIMITED**, Hyderabad (IN)

(**) Term: **15 Years**

(21) Appl. No.: **29/724,187**

(22) Filed: **Feb. 13, 2020**

(30) **Foreign Application Priority Data**

Aug. 13, 2019 (IN) 320643-003

(51) LOC (13) Cl. **14-03**

(52) U.S. Cl.

USPC **D14/218**; D13/168

(57) **CLAIM**

The ornamental design for a wireless controller for simultaneous multiple device operation, as shown and described.

DESCRIPTION

FIG. 1 is a front elevation view of a wireless controller for simultaneous multiple device operation, showing our new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a front perspective view thereof.

1 Claim, 7 Drawing Sheets
